UNITED STATES PATENT OFFICE.

OTTO A. LEHMAN, OF HOBOKEN, NEW JERSEY.

DESIGN FOR A LADY'S HAND-BAG.

SPECIFICATION forming part of Design No. 20,153, dated September 9, 1890.

Application filed July 2, 1890. Serial No. 357,565. Term of patent 3½ years.

To all whom it may concern:

Be it known that I, OTTO A. LEHMAN, of Hoboken, in the county of Hudson and State of New Jersey, have invented and produced a new and original Design for Ladies' Hand-Bags, of which the following is a specification, reference being had to the accompanying drawings, forming a part thereof.

Figure 1 is a side view of a bag of my design. Fig. 2 is an edge view of the same.

Similar letters of reference designate corresponding parts in both figures.

My design consists of the body having flat sides, the lower corners, the edges, and the bottom of which are rounded, and a head which is contracted upward from the body with an irregular surface and which has a ruffle above said contraction, the body having upright loops and the head having dependent loops.

A designates the body, having flat sides *a*, as shown in Fig. 2, rounded lower corners *b*, as shown in Fig. 1, the bottom rounded in its transverse profile, as shown at *c* in Fig. 2, and having a continuous bead *d* running along the center of the bottom and up the sides.

B is the head, contracted upward from the body with an irregular surface, as shown at *e*, and having the ruffle *f* at the top. The loops *C* project upward from the flat sides *a* of the body below the head, and the loops *D* depend from the head below the ruffle *f*.

What I claim as my design is—

The design for a lady's hand-bag, substantially as herein shown and described.

OTTO A. LEHMAN.
